UNITED STATES PATENT OFFICE.

GEORGE SOLARZ, OF GALLITZIN, PENNSYLVANIA.

ICE CREEPER.

Application filed July 23, 1925. Serial No. 45,672.

To all whom it may concern:

Be it known that I, GEORGE SOLARZ, a citizen of the United States, residing at Gallitzin, in the county of Cambria and State of Pennsylvania, have invented a new and useful Ice Creeper, of which the following is a specification.

This invention aims to provide a creeper for shoes, so constructed that it may be applied to articles of foot wear of different widths, the device being so made that it will have an unusually strong hold on the ice, slippery logs and the like, it being impossible for the shoe-strap to become detached from the body portion of the article.

It is within the province of the disclosure to improve generally and to enhance the utility of devices of that sort to which the invention appertains.

Although a preferred form has been shown, a mechanic, working within the scope of what is claimed, may make changes in that form, without departing from the spirit of the invention.

In the drawings:—Figure 1 is an end elevation; Figure 2 is a side elevation showing the device as it will appear on a shoe of medium width; Figure 3 is a view similar to Figure 2 but showing the article as it will appear on a wide shoe.

The device forming the subject matter of this application comprises a metal body 1 provided at its ends with depending anti-slipping members 2. Loop-shaped riders 3 are adjustable longitudinally of the body. The riders 3 are connected by a shoe-engaging means 4 which may embody a strap wherein a buckle is interposed. When the device is used with a shoe the sole 5 of which

is of medium or small width, the riders 3 are engaged in any one of a plurality of seats 6 formed in the lower surface of the body 1. When the device is used with a shoe the sole 7 of which is unusually wide, the riders 3 may be adjusted downwardly on the anti-slipping members 2. The lateral edges 8 of each anti-slipping member diverge downwardly to prevent the riders 3 from becoming detached, and to enhance the hold of the members 2 on the ground. The hold of the members 2 on the ground is promoted, further, because they diverge from each other, downwardly, as shown at 9, and because each of them is bifurcated to form pointed prongs 10.

I claim:—

1. A device of the class described comprising a body provided at its ends with depending anti-slipping members, riders adjustable longitudinally of the body, and shoe-engaging means connecting the riders, the riders being adjustable downwardly on the anti-slipping members, the lateral edges of said members diverging downwardly to enhance the hold of said members on the ground and to prevent the riders from becoming detached.

2. A device of the class described, constructed as set forth in claim 1, and further characterized by the fact that the body is provided on its under surface with a plurality of seats wherein the riders may be held, in adjusted positions longitudinally of the body.

In testimony that I claim the foregoing as my own, I have hereto affixed my signature.

GEORGE SOLARZ.
